UNITED STATES PATENT OFFICE

HANS C. M. JENSEN, OF CHICAGO, ILLINOIS

DESIGN FOR A MINIATURE AQUARIUM

Application filed May 21, 1930. Serial No. 35,704. Term of patent 3½ years.

To all whom it may concern:

Be it known that I, HANS C. M. JENSEN, a citizen of the United States, residing at Chicago, in the county of Cook and State of Illinois, have invented a new, original, and ornamental Design for a Miniature Aquarium, of which the following is a specification, reference being had to the accompanying drawing, forming part thereof.

Fig. 1 is a side view of the miniature aquarium embodying my design both sides of the aquarium being similar; and

Fig. 2 is an end view of the miniature aquarium embodying my design.

I claim:

The ornamental design for a miniature aquarium substantially as shown and described.

HANS C. M. JENSEN.
